JOHN J. WITT, OF WINCHENDON, MASSACHUSETTS, ASSIGNOR TO GOODSPEED MACHINE COMPANY, OF WINCHENDON, MASSACHUSETTS, A CORPORATION OF MASSACHUSETTS.

MACHINE FOR TURNING BOBBIN BLANKS.

Application filed June 29, 1925. Serial No. 40,382.

This invention relates to improvements in machines for turning bobbin blanks and the object thereof is to provide a machine which will turn bobbin blanks accurately and with

5 greater speed than has heretofore been accomplished. In the manufacture of bobbins for use in looms it is desirable that the grain of the wood shall run in the direction of the axis of the bobbin and to insure this relation 10 of the grain of the wood to the axis of the bobbin it has been customary to split the blanks from which the bobbins were to be constructed from suitable blocks of wood. This not only required highly skilled labor, but 15 resulted in considerable wastage of stock. Furthermore the split blocks were necessarily of more or less irregular character and required great care in centering the blocks upon the lathe and in turning them. It has 20 been found that wholly satisfactory bobbins can be made from sawed blocks by first carefully slabbing a substantially knotless section of a tree trunk, or a limb, in parallelism with the heart thererof, then cutting the slabs at 25 right angles to their surfaces in parallel, substantially square, sections preferably by means of a gang-saw to produce blocks in which the grain of the wood runs in the direction of the axis of the block, then turning the 30 blocks down to form bobbin blanks and thereafter producing the bobbin from the bobbin blanks thus provided.

The present invention relates to a machine for rapidly and accurately turning bobbin 35 blanks from substantially rectangular blocks of a character above described and the principal object thereof is to provide means for rapidly and accurately turning the blocks into bobbin blanks comprising a substantially 40 cylindrical barrel with an enlarged cylindrical base which merges in a gradual curve into the barrel.

Another object of the invention is to provide a machine in which the bobbin blank 45 can be turned from a block in a single operation by means of a knife having an edge conforming to the profile of the bobbin blank. In thus turning a bobbin blank from a rectangular block with a knife of this character the 50 portion of the blade of the knife which turns down the barrel of the bobbin blank will engage the angular portion of the rectangular block in advance of the engagement there-

with by the portion of the knife which turns down the base portion of the bobbin blank, 55 thereby producing an unequal torque upon the ends of the block.

Another object of the invention is to provide independent, positively acting, continuously rotating means engaging the ends of the 60 bobbin blank which may be so adjusted as to produce proper synchronous rotation of both ends of the bobbin blank irrespective of the difference in power required by the respective driving means to produce such synchronous rotation. This is accomplished in the present invention by providing a pair of axially alined live spindles with means for rotating the same in synchronism. Preferably this means comprises a pair of independently operable belt mechanisms for the respective spindles with means for adjusting the tension of the respective belts adapted to cause the required degree of power to be transmitted by the respective belts to the 75 spindles.

Another object of the invention is to provide means for varying the field of movement of the knife in order that bobbin blanks of different diameters may be produced. 80

A further object of the invention is to provide means for adjusting the relative position of the spindles in order that bobbin blanks of different lengths may be produced.

Another object of the invention is to provide means for relatively moving the live 85 spindles longitudinally during the continuous rotation thereof to release a turned bobbin blank and to dog a fresh block in combination with means operating in timed relation with such relative movement for positioning a fresh block in axial alinement with the spindles so that the grain thereof shall run in the direction of the axis of rotation, means also preferably being provided to 90 knock off the turned bobbin blank from the spindles during the releasing movement.

These and other objects and features of the invention will more fully appear from the following description and the accompanying 100 drawings and will be particularly pointed out in the claims.

In the drawings:

Fig. 1 is a vertical transverse sectional view of a bobbin blank turning machine embodying the invention; 105

Fig. 2 is a detail view, in transverse section, illustrating particularly the knock-off mechanism and the mechanism for manually controlling the feeding of the block to the 5 relatively movable live spindles;

Fig. 3 is a rear elevation of the machine;

Fig. 4 is a plan view of the machine showing 10 a positioned block ready to be engaged or dogged by the live spindles, the cutting 15 and knock-off mechanism being omitted;

Fig. 5 is a similar view showing the block 20 after it has been engaged or dogged by the spindles and in position to be turned; and,

Fig. 6 is a perspective view illustrating 25 the knife having its edge shaped to conform to the profile of the bobbin blank and its relative position to a block to be turned.

The machine illustrated in the drawings 30 comprises a bed formed of two oppositely disposed bed rails, preferably channel bars 1 and 2, which are supported at their ends upon suitable standards 3 and 4, the bed serving to support the turning and feeding mechanism and the standards providing means for 35 supporting the driving shaft, the cam shaft and other actuating mechanisms. A pair of heads 5 and 6 rest upon and are secured to opposite ends of the bed rails 1 and 2. The head 5 is provided at its ends with upwardly 40 extending members or arms 7 and 8 providing sections of bearings for a rotatable or live spindle 9, the bearings 7 and 8 being provided with complementary caps 10 and 11 having suitable grease cups. The outer end of the 45 spindle 9 is rotatably mounted in a block 12 and abuts against a suitable thrust bearing which is adapted to be adjusted by a screw 13 seated in the end of the block 12 and adapted to be clamped in position by a suitable 50 lock nut. The block 12 has secured to its lower end a short shaft 14 which is adjustably secured to a boss on the head 5 by a suitable set screw 15. By reason of this construction the block 12 may be adjusted toward and from 55 the end of the head 5 so that the end of the live spindle may be properly positioned with relation to the mechanism which feeds and positions blocks in dogging position relatively to the spindle.

50 The other head 6 likewise is provided with upwardly extending arms or members 16 and 17 forming parts of journals of a live spindle 18 which is in axial alignment with the spindle 9 and these members likewise are provided 55 with suitable caps to complete the respective bearings. The spindle 18 is rotatably secured in the end of a block 19 the outer end of which is bifurcated and provided with a transverse pin 20 to which is connected a link 60 21 which is pivotally connected to the bifurcated upper end of a lever 22 which is fulcrumed upon a stud shaft 23 extending laterally from a block 24 which is adjustably mounted in a rectangular way 25 in a bracket 65 26 secured to the bed of the machine. The

block 24 is adjusted by means of a screw 27 which is seated in the end of the bracket 26 and engages the block 24. The lower end of the lever 22 is provided with an anti-friction roller 28 which engages a cam 29 upon a cam 70 shaft which is mounted in suitable bearings in the standards 3 and 4. The roller 28 is held in engagement with the cam by means of a spring 31 which is secured at one end to the lower arm of the lever 22 and at its other end to the end of the standard 4.

The spindles 9 and 18 desirably are independently driven, preferably by belt mechanisms. As illustrated herein a main driving shaft 32 is mounted in suitable bearings upon 80 a transverse member 33, (see Fig. 1), of the standards 3 and 4 and may be provided at either end with suitable fast and loose pulleys 34 and 35. The shaft 32 has fixedly secured to it a belt pulley 36 which actuates a 85 belt 37 which drives a belt pulley 38 which is fixedly secured to the spindle 9, and desirably is provided with a balance wheel 38* which stores up sufficient power to cause substantially uniform speed of rotation of the 90 spindles as the block is engaged by the knife. This is essential as in the construction illustrated the knife is so positioned that the portion of the blade 62, which turns the barrel of the blank, is adjacent to the spindle 9. 95 Consequently the turning down of the rectangular block is begun at the end of the block which is nearest the spindle 9 and a relatively greater torque is imposed upon the spindle 9 than upon the spindle 18. By providing independent adjustments for tensioning the belt 37 from that which acts upon the belt which drives the spindle 18 these belts can be so adjusted as to transmit proper torque to the respective spindles to maintain a synchronous rotation of both spindles. 105

Suitable means are provided for adjusting the tension upon the belt 37. The belt-tightening mechanism which is illustrated herein comprises a lever 39 which is mounted 110 at its lower end upon a suitable pivot 40 carried by the standard 3, or a bracket projecting therefrom, and at its upper end is provided with a roll 41 which engages the belt 37. A U-shaped link 42 straddles the lever 115 39 and is pivotally connected thereto. A screw 43 is engaged in the transverse portion of the U-shaped link 42 and extends through a sleeve 44 which is pivotally mounted upon a stud 45 fixedly secured to the standard 3. 120 The screw 43 has at its end a hand wheel 46 which abuts against the end of the sleeve 44. By rotating the hand wheel 46 the screw is caused to adjust the position of the lever 39 and consequently adapted to cause the roll 125 41 to press against the belt 37 with greater or less force as may be required.

The shaft 32 is also provided with a belt pulley 47 similar to the belt pulley 36. The belt pulley 47 drives a belt 48 which passes 130

over and drives a belt pulley 49 which is fixedly secured to the shaft 18. Belt-tightening means, similar to the belt-tightening means heretofore described comprising the lever 39, 5 the roll 41, link 42 and screw 43, is provided for adjusting the tension upon the belt 48. By reason of this construction the tension of the belts 37 and 48 respectively can be varied in such a manner as to cause the power transmitted thereby to produce synchronous rotation and the required torque upon the opposite ends of the block which is carried by the spindles and being turned down by the knife.

The preferred cutter mechanism which is 15 illustrated herein is in the form of a heavy block comprising parallel upper and lower plates 50 and 51 having integral end arms 52 and 53 which are pivotally mounted upon conical screws 54 and 55 respectively seated 20 in arms 56 and 57 of a bracket 58 the body of which is connected by bolt and slot connections 59 to a supporting block 60 which is fixedly secured to the bed rails 1 and 2 substantially centrally of the machine. The 25 bracket 58 is adapted to be adjusted vertically by a plurality of set screws 61 which pass through a rearwardly extending flange upon the block 60 engaging the under side of the bracket 58, it being understood that the bolts 30 59 will be loosened during the adjustment and set-up when the desired adjustment is produced. By reason of this adjustment the knife may be properly positioned as will hereinafter more fully appear.

35 The knife 62 is located between the upper and lower plates 50 and 51 and clamped against the upper plate by a plurality of screws 63 which are seated in the block 50 and abut at their upper ends against the blade 62. 40 The plate 51 is provided at its inner end with an upwardly extending relatively thick flange 64 to which is secured a plurality of adjustable gauges 65 which may be positioned in predetermined relation to the edge of the 45 knife. An outwardly diverging aperture 66 through the plate 51 and its flange 64 provides means for discharging the shavings from the knife. The knife-supporting members and knife are heavy as before stated and feed the knife to the work by the action of 50 gravity. The descent of the knife may be controlled by any suitable mechanism. In the embodiment of the invention illustrated herein the central portion of the plate 50 of 55 the knife-supporting mechanism rests upon the upper end of a post or rod 67 the lower end of the post being provided with a conical socket which receives the conical end of a screw 68 which is adjustably seated in a boss 69 in the central portion of a lever 70 which 60 is fulcrumed upon a stud 71 projecting from a bracket which depends from the bed rails 1 and 2. The opposite end of the lever 70 is provided with an anti-friction roll 72 65 which rests upon the periphery of a cam 73

which is fixedly secured to a cam shaft 74 journalled in suitable bearings in the standards 3 and 4. The cam 73 is of such form as to cause the rapid raising of the lever 70 to raise the knife after the completion of the cutting operation and gradually to permit the knife to descend during the cutting action thereof.

Suitable means are provided for feeding the blocks to the spindles and positioning the 75 same between the ends of the spindles during the relative longitudinal movement of said spindles and positioning means are also provided for holding the positioned block in accurate alinement with the axis of the spindle until the dogging movement of the spindles, these mechanisms being so timed that when the centers of the spindles have engaged the ends of the positioned block the feeding 80 mechanism and positioning mechanism will 85 be withdrawn to permit immediate rotation of the block as the dogs upon the ends of the spindles engage the ends of the positioned block.

The block-supporting and feeding mechanism 90 comprises a table 75 which is reciprocably mounted upon a bracket 76 which is adjustably secured to the bed rail 2 by a bolt and slot connection 77 and which is adjusted vertically by suitable screws 78 passing 95 through a flange or boss extending laterally from the lower portion of the bed rail 2 and abutting on the under face of the bracket 76. The table is guided between lateral ways 79 and 80 which are secured to the bracket 76. 100 A feeding belt 81 passes over the table 75 and around rollers 82 and 83 at the outer and inner ends of the table and also around a belt-tightening roller 84 which is carried at the end of arms 85 pivotally mounted upon the 105 bracket 76. The belt-tightening roller is forced against the belt by a spring 86 which may be secured to the frame in any suitable manner (not shown). The roller 82 has secured to its end or to its shaft a ratchet 87 110 which is engaged by the toothed outer end of a rack 88, the inner end of which is pivotally mounted upon a stud 89 upon the bracket 76, the rack being held in engagement with the ratchet 87 by a leaf spring 90 which is secured to the under face of the bracket and 115 bears upwardly upon the rack.

The blocks from which the bobbin blanks are to be turned are positioned upon the belt and are held down upon the belt by a suitable 120 spring 91 which extends longitudinally of the blocks toward the knife, the outer end of the spring curving upwardly and downwardly into a loop the end of which is secured to a rod 92 carried by an arm 93 projecting upwardly from the edge of the table 75.

Suitable means are provided for reciprocating the table and coincidently advancing the belt to cause it to feed the blocks to the spindles. As illustrated herein a U-shaped 125

member 94 is secured to the side of the table and a shaft 95 is reciprocably mounted in suitable bearings in the arms of this U-shaped member. The ends of the shaft 95 are provided with collars 96 and springs 97 are interposed between the respective collars and the outer face of the arms of the U-shaped member 94. A collar 98 is secured to the shaft 95 between the arms of the U-shaped member 10 and is provided with a downwardly extending arm which is pivotally connected by a stud 99 to one end of a link 100 the opposite end of which is pivotally connected to the upper end of a substantially vertical arm 101 of 15 a bell crank lever which is fulcrumed upon a stud shaft 102 carried at the lower end of brackets 103 which are secured to the under face of the bed rails 1 and 2. The other arm 104 of the bell crank lever has at its end a 20 laterally extending roller 105 which runs in the groove of a substantially heart-shaped cam 106 which is secured to the cam shaft 74. This cam is of such shape as to cause the table to dwell during the turning of the bobbin 25 blank from the block and then rapidly to advance the table relatively to the position of the spindles (to the right as illustrated in Fig. 1) and also rapidly to retract the same after the block has been engaged by the spindles. As the table is thus moved by the heart-shaped cam toward the spindles the toothed rack 88 by its engagement with the ratchet 87 upon the roller 82 causes the roller 82 to rotate and drives the upper lead of the 30 belt in the direction of movement of the table, that is to the right as illustrated in Fig. 1, thus feeding the blocks along the table as the table is advancing and finally forcing the block forward so that the block of the series which 35 is to be positioned will rest upon an extension 40 of the table and project slightly therebeyond as the table reaches its maximum movement toward the spindles. This movement will position the axis of the block directly in 45 alignment with the axis of the spindles which at this time have been separated by the lever 22 and cam 29 as above described.

Suitable means are provided for assisting in positioning the block in axial alignment 50 with the spindle as will hereinafter be described. The cam shaft which actuates the cutter and the feeding mechanism is driven by a countershaft from the main driving shaft at a greatly reduced speed and is manually controlled by the following mechanism. 55 The countershaft 108 is mounted at one end in a bearing in a transverse member of the standard 3 and at its opposite ends in a boss 108* extending forwardly from one of the brackets 60 103 and is provided with a belt pulley 109 which is driven by a belt 110 from a much smaller belt pulley 111 on the main shaft. A train of gears transmits the rotation of the countershaft 108 to the cam shaft and preferably these gears are so constructed as to per-

mit the changing of gears to transmit different speeds of movement from the counter-shaft to the cam shaft.

Any suitable well known change gear construction may be employed for this purpose. 70 As illustrated herein a pinion 112 upon the end of a countershaft engages an idle gear 113 which is mounted upon a stud shaft 114 extending from a boss 115 carried by a bracket 116 which is secured to the frame, the boss 115 and its stud shaft 114 lying beyond the vertical plane of the gear 112. A relatively small pinion upon the stud shaft 114 and which may be made integral with the gear 113 engages a gear 117 upon the cam shaft 74. 80 Thus a sufficient reduction is produced to provide for the proper rotation of the cam shaft 74.

The operation of the countershaft and the cam shaft is manually controlled by means 85 acting upon the belt 110 to cause it either to drive the countershaft or to permit such slippage of the belt as effectively to arrest the rotation of the countershaft and cam shaft. The mechanism for accomplishing this purpose comprises a belt-tightening pulley 118 which is mounted upon a shaft 119 projecting from the end of one arm 120 of a bell crank lever which is pivotally mounted upon a stud projecting from a boss 121 on one of the brackets 103 which depend from the bed rails 1 and 2. The other arm 122 of the bell crank lever is connected to a link 123 which is pivotally mounted at its upper end upon a pivot 124 carried by a disk 125 fixedly secured upon a shaft 126 which is mounted in suitable brackets 127 projecting from the side of the bed rail 2. The shaft 126 has a hand lever 128 secured to it. The pivot 124 is so located 90 upon the disk that when in the position illustrated in Fig. 2 the belt-tightening pulley 118 will be forced firmly against the belt, but when the lever 128 is swung over to the left from the position illustrated in Fig. 2 95 the pivot 124 will be carried beyond the axis of the shaft 126 and permitted to descend sufficiently to release the belt-tightening pulley 118 from effective engagement with the belt, thereby loosening the belt and providing 100 the slippage above referred to. Thus the operator will at all times have control of the feeding mechanism and coincidentally also the knife-actuating mechanism, both of 105 which are actuated from the cam shaft. 110

The positioning mechanism for properly 115 locating the blocks which are advanced by the feed table in axial alignment with the spindles which is illustrated herein comprises an abutment 129 in the form of an arm, the outer end of which is adapted to engage a 120 block when it reaches the proper position relatively to the center of the spindle, the opposite end of the gauge being provided with a bolt and slot connection 130 to the cutter-supporting block 60. A movable 125

gauge 131 is adapted to engage the opposite end of the block, the gauge 131 being in the form of a substantially L-shaped arm which is pivotally mounted upon a stud 132 extending upwardly from an adjustable plate 133 which is pivotally connected at its opposite end by a bolt 134 to the cutter-supporting block and is provided intermediate of its ends with a slot through which a clamping screw 135 passes into the block 60. The central portion of the L-shaped gauge member 131 is connected by a link 136 to an arm 137 which projects outwardly from the block 19 which is connected to the live spindle 18. Desirably the connection between the link 136 and the arm 137 is adjustable and as shown herein comprises a small block 138 through which the link 136 passes and is secured thereto by a set screw 139. The block 138 is pivotally connected to the arm 137 by a bolt 140.

The laterally extending arm 137 is also provided with a boss 141 to which is connected a rod 142 which extends through the arms 16 and 17 of the head 6. The rod 142 is provided with a collar 143 which engages one end of a helical spring 144 the opposite end of which abuts against the upwardly extending arm 17 of the head. The spring 144 therefore tends to force the spindle longitudinally away from work-engaging position and aids in forcing the lower end of the lever 22 against the cam 29.

In the operation of the machine as the live spindle 18 is moved longitudinally (to the left) the link 136 is drawn to the left rocking the gauge 131 about its pivot to the position illustrated in Fig. 4, while the movement of the live spindle 18 to the right causes the link 136 to move longitudinally in the opposite direction, thereby rocking the gauge 131 out of engagement with the end of the block as illustrated in Fig. 5. The movement of the spindle after its center has engaged the end of the block forces the block laterally into engagement with the dogs of the opposite axially alined spindle and moves the block beyond the gauge 129 to the position illustrated in Fig. 5 so that as the block is dogged it is freed from engagement with both the gauges 129 and 131. In the meantime the table will move backward so that the block is free to rotate and to be turned down by the descending knife.

A suitable knock-out mechanism is provided for discharging the turned bobbin blank from the spindles during the axial releasing movement of the spindle 18. This mechanism, which is particularly illustrated in Fig. 2, comprises a hammer 145 carried by the end of an arm 146 which is pivotally mounted upon a stud 147 in the upper end of a bracket 148 which is secured to the upper face of the bed rail 2. A link 149 is pivotally connected to the arm 146 intermediate of its

pivot and the hammer 145 and the lower end of the link 149 which is twisted through ninety-degrees is pivotally connected to the outer end of a lever 150 which is fulcrumed upon the countershaft 108. The opposite end of the lever 150 is provided with a cam follower roll 151 which engages the groove of a cam 152 which is fixedly secured to the cam shaft 74. The cam 152 is so shaped and so positioned that the lever 150 will be rocked about its pivot shortly after the live spindle 18 is withdrawn longitudinally from engagement with the end of the bobbin blank so that the hammer 145 will be caused to descend and strike the turned bobbin blank and discharge it from the spindles.

In the operation of the machine the belt is first shifted from the loose pulley 35 to the tight pulley 34 of the driving shaft so that the spindles are rotated through their respective driving belts 37 and 48, these spindles being continuously rotated during the operation of the machine. Rectangular blocks of wood A, which as above described, have been so sawed that the grain runs in the direction of the axis of the blocks are placed upon the upper lead 81 of the belt which runs along the surface of the table 75, the blocks being shoved under the hold-down spring 91 as illustrated in Fig. 1. Other blocks can be successively placed upon the belt as the forward blocks are successively turned down by the machine. The feeding mechanism is then started by swinging the hand lever 128 to the position illustrated in Fig. 2. This causes the belt-tightening roller 118 forcibly to engage the driving belt 110 of the countershaft 108 and thereby to rotate the belt pulley 109 and the countershaft 108. The power from the countershaft is transmitted through the train of gears to the crank shaft 74. The rotation of the crank shaft causes the cam 106 to depress the follower roller 105 of the arm 104 of the bell crank lever so that the other arm 101 of the lever, acting through the link 100, reciprocates the table toward the spindles to the right of the position shown in Fig. 1. This bodily movement of the table causes the engagement of the ratchet 87 with the toothed rack 88 to rotate the roller 82 which drives the feeding belt 81 so that the blocks which rest upon the belt are advanced simultaneously with the movement of the table toward the spindles so that the first block is positioned accurately with respect to the center of the spindles. This positioning is insured by the engagement of the block with the gauges 129 and 131 (see Fig. 4). The table is permitted to yield when the block engages the gauges 129 and 131 by

reason of the resilient connections formed by the shaft 95 to which the link 100 is connected through the arm 98, this resilient connection comprising the springs 97 which are located upon opposite sides of the arms of

the bracket 94 and between said arms and the 5 collars 96 which are secured upon the shaft 95. Thus the center of the block is placed in accurate alinement with the centers of the spindles so that the grain of the wood runs in the direction of the axis of the alined 10 spindles. As soon as the block is thus positioned the cam 29, acting upon the lever 22, rocks the lever about its fulcrum 23 and forces the spindle 18 longitudinally into 15 engagement with the end of the block. The spindle continuing its movement forces the block against the opposite spindle, thus dogging the block upon both spindles. This longitudinal movement of the block frees it 20 from the gauge 129. The longitudinal movement of the spindle also simultaneously moves the rod 136 longitudinally thereby swinging the pivotally mounted dog 131 out of engagement with the block as illustrated in Fig. 5, thus freeing the block at the time it is dogged by the spindles.

This dogging of the block upon the spindles is accomplished by a very rapid movement 25 as will be readily noted by observation of the contour of the cam 29. Immediately after the block has been dogged by the spindle the knife is permitted to descend, the descent of the knife being controlled through the vertical post or rod 67 which is connected 30 to the lever 70 which has upon its end the follower roll 72 engaging the surface of the cam 73. During the downward movement of the knife the follower 72 rests upon the gradually curved surface of the cam 73 so that the descent of the knife is relatively slow. The knife first engages the portion of the block which is adjacent to the spindle 9 which is held against longitudinal movement 35 of the block. The tension of the belt 40 and vibration of the spindle is effectively overcome by the power stored up in the fly wheel which is secured to the spindle 9 and by the relatively tight belt mechanism which drives the spindle 9. The tension of the belt 45 which drives the spindle 18 may be adjusted by the belt-tightening mechanism which engages it so that synchronous rotation of the spindles will be insured as well as the application of the proper torque to the opposite ends 50 of the block to insure the proper cutting operation of the knife.

When the knife has descended sufficiently to complete the turning of the bobbin blank the cam 73 rapidly raises the knife from its lowest position illustrated in Fig. 1 to its highest position. At this time the cam 29 operates to move the spindle 18 longitudinally to release the turned bobbin blank. During this releasing movement the knock-off hammer 145 is actuated through the link 149 and lever 150 by the cam 152 to cause the hammer 145 to strike the blank and discharge it into a suitable chute which delivers it from the machine.

65. The feeding of the bobbin blanks to the

turning mechanism may be arrested by swinging the lever 128 from the position illustrated in Fig. 2 to the left until the pivot 124 of the link is carried over the vertical plane of the center of the shaft 126 and downwardly so that the bell crank 122, which carries the belt-tightening roller 118, will carry the roller away from effective belt-tightening engagement with the belt 110.

The field of operation of the knife 62 can be adjusted by varying the position of the rod 67 by adjusting the screw 68 which engages the end of the rod. The machine can be set to turn bobbins of different lengths by adjusting the position of the fulcrum 23 of the lever 22 which moves the spindle axially although under ordinary conditions the table of the machine will be constructed in such a manner that the edges of the table will lie closely adjacent to the ends of the blocks.

It will be understood that the particular embodiment of the invention described herein is of an illustrative character and is not restrictive and that various changes may be made in form, construction and operation 90 within the spirit and scope of the following claims.

Having thus described the invention, what is claimed as new, and desired to be secured by Letters Patent, is:

1. A machine for turning from a rectangular wooden block a bobbin blank having a base of relatively larger diameter than that of the barrel of the blank comprising a knife presenting an edge conforming to the profile of the bobbin blank and means for feeding the knife to the block, a longitudinally immovable belt driven spindle having means to engage the block at the end which is to be turned down to the smaller diameter, a fly wheel fixedly secured to said spindle operable to compensate for the heavier duty imposed upon said spindle by the greater resistance of the portion of the knife adjacent thereto, a co-operating longitudinally movable belt driven live spindle axially alined with said longitudinally immovable spindle, and independent means for adjusting the tension of the spindle driving belts to insure synchronous rotation of said spindles.

2. A machine for turning blanks from rectangular blocks comprising a pair of axially alined live spindles, means for rotating the spindles at the same speed, a knife, means for automatically feeding the knife relatively to said block, means for reciprocating one of said spindles axially first to release a turned blank and then to dog a fresh block, means automatically operable in timed relation to the axial movement of said reciprocating spindle to position a fresh block between said spindles in axial alinement therewith, a fixed stop so positioned as to engage the block adjacent the end thereof which is to be engaged by the axially movable spindle and to be dis-

engaged when said block is moved longitudinally upon the dogging action of said spindle, a swinging stop positioned to engage the opposite end portion of the block, whereby the positioning of the block relatively to the spindles is insured and means connecting said swinging stop to said axially movable

spindle operable during the dogging movement of said spindle to remove said stop from engagement with said block. 10

In testimony whereof, I have signed my name to this specification.

JOHN J. WITT.
